UNITED STATES PATENT OFFICE

2,313,683

GASEOUS DISCHARGE LAMP

Richard N. Thayer, Cleveland Heights, Ohio, assignor to General Electric Company, a corporation of New York

Application March 28, 1941, Serial No. 385,661

12 Claims. (Cl. 176—122)

My invention relates to gaseous discharge lamps having preheated thermionic cathodes, for example, those lamps of the fluorescent type shown and described in the U. S. Patent No. 2,182,732 to Meyer et al. More particularly the invention relates to an improved means for preheating the cathodes and for initiating the discharge after such preheating. The invention consists in the new and novel arrangement of elements hereinafter disclosed and claimed.

In most gaseous discharge lamps of the aforesaid type, it has generally been necessary to provide means for passing a preliminary heating current through the cathodes and for subsequently automatically discontinuing said preliminary current and simultaneously initiating the main discharge when the cathodes have reached emitting temperature. This requirement arises from the fact that the cathodes are subject to damaging positive ion bombardment if the current is drawn from them before they begin to emit electrons in substantial quantities. In most commercially successful arrangements the problem is solved by passing current through the cathodes in series and by providing temperature or current responsive means to break the series connection when the desired cathode temperature is reached. Many such arrangements have been devised but all have been subject to some objectionable features, such as high cost, complexity, bulkiness, relatively short useful life, and/or improper cathode heating. By my improved construction, I have provided a simple and effective lamp starting means of this type which avoids many of these objections and which permits the incorporation of the discharge producing members and the starting means within a single envelope.

Generally speaking, the objects of the invention are accomplished by providing a bimetallic member adjacent to the cathode and arranged to operate a pair of contacts which control the series preheating circuit. The ideal preheating control will insure that during the starting operation the cathode is neither too cold, which would cause its rapid destruction by positive ion bombardment, nor too hot, which would foster rapid evaporation. By my construction it is possible to approach this ideal preheating control much more closely because the controlling elements are responsive to cathode temperature itself rather than to the temperature of the lamp as a whole or to completely independent conditions as is the case with many of the arrangements now common in the art.

It is accordingly an object of my invention to provide a new and improved starting means for discharge lamps, which means shall be simple in construction and economical in manufacture.

5 It is a further object of the invention to provide a new and improved discharge lamp in which the starting means may be incorporated directly within the lamp and which shall depend directly upon the cathode temperature for operation.

10 It is still a further object of the invention to provide a new and improved thermostatically operated unit for automatically discontinuing the cathode preheating operation in lamps of the aforesaid type and thereafter automatically initiating the discharge.

15 Further objects and advantages of the invention will be apparent from the following detailed description thereof and from the accompanying drawing in which the Fig. 1 shows a lamp constructed in accordance with the invention along with a circuit for operating the same, while Fig. 2 shows in perspective and in greater detail the improved starting and cathode unit. The Fig. 3 shows schematically the geometrical configuration of the bimetallic switching unit, while the Fig. 4 shows an alternative modification of the lamp shown in Fig. 1. Corresponding numerals will indicate like parts throughout.

20 Referring to the drawing, the lamp shown in Fig. 1 comprises generally an envelope 10 having mounted therein a pair of thermionic cathodes 11 and 12 of the conventional coiled type, as well as a filling of mercury vapor which may be provided by a globule of mercury 13. A starting gas such as one of the rare gases at pressures up to several millimeters may also be provided in the usual manner. The cathode 12 is also pro-

25 vided with a pair of auxiliary electrodes 14 one of which is attached to each end thereof. These serve as the anodes of the lamp during that portion of the cycle in which the cathode 12 is at higher potential than cathode 11. The cathode 11 is provided with but one auxiliary anode 14, 30 while in place of the other is substituted the coiled bimetallic strip 15 mounted on an extension 16 of the cathode lead wire. As shown, the bimetallic strip 15 is in close proximity to the cathode 11 and is attached at its free end to a

35 sliding plunger or contact 16. The plunger 16 is arranged to slide in the open end of capillary tube 17, which is fused to the stem press 18 of the lamp and mounted co-axially with the lamp. At the lower or closed end of the capillary 17 is 40 positioned a second and preferably fixed contact

45 50 55 60 65 70 75 80 85 90 95 100

19 which is arranged to make contact with the sliding plunger 16. The leads 20 are arranged to electrically connect both the contact 19 and the one side of the cathode 11 to the base contact members 21 and 22 positioned on the outside of the base 32. The lead 23, which is connected to the opposite side of the cathode 11, is provided only for the purpose of electrically heating the cathode 11 during the process of manufacture, and may be cut short before the lamp is finally mounted in the base 32. In a similar manner, the cathode 12 is electrically connected to the contact members 24 on base 37 by means of the leads 25. The envelope may be provided with an inner coating of fluorescent material 26 in the usual manner.

The bimetallic strip 15 is preferably constructed in the semicircular form shown in Fig. 3 for the reason that, for a given length of bimetal, this form permits the closest spacing of the strip to the cathode. It will be understood that it is desirable to space the bimetal as closely as possible to the cathode without destroying its temper by excessive heating in order that it will follow as closely and as quickly as possible the temperature variations thereof. If it is spaced too far from the cathode, it will tend to follow the temperature variations of the walls rather than those of the cathode. The bimetallic strip 15 should be oriented so that it draws contact 16 from the capillary tube without binding. I have found that this can be accomplished by so positioning the strip that the chord or diameter subtending its ends is at an angle to the direction of motion of the contact 16 as shown in Fig. 3. For the semicircular strip this angle is about 40°.

For the purposes of completeness, the following dimensions of the various parts of the switching unit shown might be noted. Those given were found to be suitable dimensions for a 100 watt fluorescent lamp. The bimetallic strip in this case consisted of a strip of Chase Company's No. 2400 bimetal having the dimensions 20 mm. by 2 mm. and being 6 mils thick. It was bent into the form of a semicircle of 12.5 mm. diameter having the cathode at the center of curvature. The capillary 17 was formed of a glass tube having an internal diameter from 40 to 45 mils, the sliding contact 16 having a diameter of from 25 to 35 mils. The pressure exerted between the two contacts when the bimetallic strip was at room temperature was adjusted to be from 40 to 50 grams. The capillary projected from 3 to 4 millimeters above the end of the fixed contact 19. With these dimensions it was found that the contacts would open in from 4 to 6 seconds after a line voltage of about 118 volts was applied to the lamp. It will be understood, of course, that all of these dimensions will be somewhat changed for lamps of different wattage. For example, in the case of the lower wattage lamps the cathodes will have a smaller heat capacity, and consequently the heating time will be much shorter.

For the purpose of energizing the lamp, any suitable source of electrical energy may be provided, such as the alternating current source 27 which is electrically connected to the lamp through the choke coil 28, the contact 22, one of the contacts 24 and the switch 29. The other of the contacts 24 and the contact 21 are connected by the external lead wire 30.

The Fig. 4 of the drawing shows a lamp in which the lead corresponding to lead 30 of Fig. 1 is placed within the lamp itself and the base 75

construction consequently simplified. In this case, the lamp is shown as a single ended lamp having the cathodes 11 and 12 as in Fig. 1, the cathode 12 being supported by the members 33 which may be ceramic or glass tubes enclosing the leads thereto. The lead 34 enclosed in left hand tube 33 and corresponding to the lead 30 of Fig. 1 will interconnect the cathodes 11 and 12 in a manner similar to that of Fig. 1. The insulating members 33 may be fused or cemented to the stem press, as shown at 35. The base 36 which may be of the conventional type is provided for the termination of the various leads. It will also be understood that the lead 30 of Fig. 1 may also be placed within the lamp shown in that figure. If that is done, only a single contact on the bases 32 and 37 will be necessary.

The operation of the lamp shown in Fig. 1 will be as follows. In the unheated condition of the lamp, the bimetallic strip 15 is so positioned as to force the plunger 16 and the contact 19 into contact with each other. When the switch 29 is closed, heating current of suitable magnitude determined by the overall impedance of the circuit will pass through the circuit comprising the choke coil 28, the lower lead 20, the cathode 11, the bimetallic strip 15, the contacts 16 and 19, lead 30, the cathode 12, and the lower lead 25. When the cathode 11 has become sufficiently heated by this current, the bimetallic strip 15 will warp to cause a withdrawal of the plunger 16 from contact with the contactor 19 and thereby open the heating circuit. Upon the opening of the circuit, a high transient voltage sufficient to start the discharge between the cathodes 11 and 12 will be developed by the inductance of the circuit. Thereafter, the bimetallic strip will be maintained in the open position by the heat from the cathode, as well as by the heating effect of the arc for which it serves as an anode during the half cycle in which it is positive with respect to cathode 12.

Hitherto, devices of this type have been unsuccessful because the arc from the cathode 11 tends to strike at the contact 19 rather than at the cathode 12. The difficulty has been solved hitherto by enclosing the contacts corresponding to 19 and 16 in a vacuum chamber within the main discharge chamber. This expedient, however, is not only costly but it also slows up the operation of the device because of the poor heat exchange between the bimetallic strip and the surrounding discharge members through the vacuum. In my construction, however, the arc is prevented from centering on the contact 19 by the capillary tube 17 and also by the fact that the plunger 16 partially closes the opening of the capillary. At the same time, the proximity of the bimetallic strip to the cathode and the heating effect of the arc foster much more rapid operation of the starting mechanism.

With my improved construction, I have been able to construct lamps in which the starting mechanism could withstand well over 15,000 individual starts. At the same time, the overall starting time of the lamp from the cold condition could be made less than 2 seconds. It will be apparent from this and from what has already been said above that I have provided a construction that is effective in operation and relatively simple and economical in manufacture.

It will be understood that in the foregoing I have described but one of the many possible embodiments of my invention, and that many variations in the structural details may occur to those

skilled in the art to which it appertains. For example, many modifications in the shape, size, and position of both capillary member 17 and the bimetallic strip 15 may be made without departing from the true spirit and scope of the invention. All such modifications I aim to include within the scope of the appended claims.

What I claim as new and desire to secure by Letters Patent of the United States is:

1. A gaseous discharge device comprising a sealed envelope having a discharge space, a gaseous atmosphere therein, at least one thermionic electrode adapted to be heated to emission temperature therein, a bimetallic switch mounted within said envelope and in heat receiving relation to said electrode, said switch comprising a chamber of insulating material open to said space, a contact in said chamber and insulated from said discharge space by the walls thereof, a second contact partially closing the opening of said chamber, a bimetallic member exposed directly to heat from said electrode and fixed at one of its ends and connected to one of said contacts at the other, whereby said contacts are separated by expansion of said bimetallic member; and means for forming a preheating circuit through said electrode by closure of said contacts.

2. A gaseous discharge device comprising a sealed envelope having a discharge space, a gaseous atmosphere therein, at least one thermionic electrode adapted to be heated to emission temperature therein, a bimetallic switch mounted within said envelope and in heat receiving relation to said electrode, said switch comprising a chamber of insulating material open to said space, a fixed contact in said chamber and insulated from said discharge space by the walls thereof, a movable contact partially closing the opening of said chamber, a bimetallic member exposed directly to heat from said electrode and connected at one of its ends to said electrode and to said movable contact at the other, whereby said contacts are separated by expansion of said bimetallic member; and means for forming a preheating circuit through said electrode through closure of said contacts.

3. A gaseous discharge lamp comprising a sealed envelope having a discharge space, a gaseous atmosphere therein, a stem press in said envelope, at least one thermionic electrode mounted on said stem press and adapted to be heated to emission temperature, a bimetallic switch mounted within said envelope and in heat receiving relation to said electrode, said switch comprising a tubular member of insulating material affixed at one end to said stem press and open to said space at the other end, a stationary contact in said tubular member and insulated from said discharge space by the walls thereof, a movable contact partially closing the opening of said tubular member and slidably therein, a bimetallic member surrounding said electrode in direct heat receiving relation thereto and connected at one of its ends to said electrode and to said movable contact at the other, whereby said contacts may be separated by expansion of said bimetallic member; and means for forming a preheating circuit through said electrode by closure of said contacts.

4. In combination, a gaseous discharge lamp comprising a sealed envelope having a discharge space and a gaseous atmosphere therein, a pair of thermionic electrodes adapted to be heated to emission temperature therein, a bimetallic switch mounted within said envelope and in heat re-

ceiving relation to one of said electrodes, said switch comprising a chamber of insulating material open to said space, a contact in said chamber and insulated from said discharge space by the walls thereof, a second contact partially closing the opening of said chamber, a bimetallic member exposed directly to heat from said electrode and fixed at one of its ends and connected to one of said contacts at the other, whereby said contacts may be separated by expansion of said bimetallic member, said bimetallic member being adapted to be heated by an arc discharge between said electrodes and said contacts and thereby held in open position; and means for forming a preheating circuit through said electrodes and said contacts in series.

5. In combination, a gaseous discharge lamp comprising a sealed envelope having a discharge space and a gaseous atmosphere therein, a pair of thermionic electrodes adapted to be heated to emission temperature therein, a bimetallic switch mounted within said envelope and in heat receiving relation to one of said electrodes, said switch comprising a chamber of insulating material open to said space, a contact in said chamber and insulated from said discharge space by the walls thereof, a second contact partially closing the opening of said chamber, a bimetallic member exposed directly to heat from said electrode and fixed at one of its ends and connected to one of said contacts at the other, whereby said contacts may be separated by expansion of said bimetallic member, said bimetallic member being adapted to be heated by an arc discharge between said electrode and said contacts and thereby held in open position; and means wholly within said envelope for forming a preheating circuit through said electrodes and said contacts in series.

6. In combination, a gaseous discharge lamp comprising a sealed envelope having a discharge space and a gaseous atmosphere therein, a pair of thermionic electrodes each mounted in a stem press and adapted to be heated to emission temperature therein, a bimetallic switch mounted within said envelope and in heat receiving relation to one of said electrodes, said switch comprising a tubular member of insulating material affixed at one end to said stem press and open to said discharge space at the other, a fixed contact in said tubular member and insulated from said discharge space by the walls thereof, a movable contact partially closing the opening of said tubular member and slidably therein, a bimetallic member surrounding said one of said electrodes in direct heat receiving relation thereto and electrically connected at one of its ends to said one of said electrodes and to said movable contact at the other, whereby said contacts may be separated by expansion of said bimetallic member, said bimetallic member being adapted to be heated by an arc discharge between the said electrodes and said contacts thereby held in open position; and means for forming a preheating circuit through said electrodes said bimetallic member and said contacts in series.

7. In an electric discharge device comprising a sealed envelope containing a thermionic electrode and a thermal switch responsive to heat from said electrode, said switch comprising a member having a comparatively small bore therein communicating with the interior of said envelope, a fixed contact projecting into said bore and terminating therewithin, a co-operating movable contact fitting comparatively snugly in said bore and arranged to slide longitudinally therein, and

a thermally responsive element located adjacent to said electrode and responsive to heat emitted therefrom, said thermally responsive element being connected to said movable contact to move it into and out of engagement with said fixed contact.

8. In an electric discharge device comprising a sealed envelope containing a thermionic electrode and a thermal switch responsive to heat from said electrode, said switch comprising a member having a comparatively small bore therein communicating with the interior of said envelope through one end and closed at its other end, a fixed contact projecting into said bore through its closed end and terminating therewithin, a co-operating movable contact fitting comparatively snugly in said bore and arranged to slide longitudinally therein, and a thermally responsive element located adjacent to said electrode and responsive to heat emitted therefrom, said thermally responsive element being connected to said movable contact to move it into and out of engagement with said fixed contact.

9. In an electric discharge device comprising a sealed envelope, an electrode and switch assembly comprising a stem of vitreous material having an integral tubular projection thereon with a comparatively small bore closed at the end adjacent said stem but open to the interior of said envelope at its opposite end, a conductor sealed through said stem and projecting into the bore of said projection through its closed end and terminating therewithin to form a fixed contact, a co-operating movable contact fitting comparatively snugly in said bore and arranged to slide longitudinally therein, a thermionic electrode carried by said stem, and a thermally responsive element carried by said stem adjacent to said electrode and responsive to heat emitted therefrom, said thermally responsive element being connected to said movable contact to move it into and out of engagement with said fixed contact.

10. In an electric discharge device comprising a sealed envelope, an electrode and switch assembly comprising a stem of vitreous material having an integral tubular projection thereon with a comparatively small bore closed at the end adjacent said stem but open to the interior of said envelope at its opposite end, a current lead-in conductor sealed through said stem and projecting into the bore of said projection through its closed end and terminating therewithin to form a fixed contact, a co-operating movable contact fitting comparatively snugly in said bore and arranged to slide longitudinally therein, a second lead-in conductor and a support wire sealed in said stem, a thermionic electrode connected

5 across said second lead-in conductor and said support wire, and a bimetallic element mounted at one end on said support wire and secured at its opposite end to said movable switch contact, said bimetallic element being in heat receiving relation to said electrode and so arranged as to move said movable contact into and out of engagement with said fixed contact.

11. In an electric discharge device comprising 10 a sealed envelope, an electrode and switch assembly within said envelope comprising a thermionic cathode, a bimetallic switch element located adjacent to said cathode, a stationary switch contact, a cooperating movable switch contact secured to the movable end of said bimetallic element and normally engaging said stationary contact but separable therefrom upon heating of the bimetallic element by said cathode, a support wire carrying and electrically connected to one end of said cathode and to the fixed end of said bimetallic element, a current lead-in conductor connected to the other end of said cathode, a second current lead-in conductor electrically connected to said stationary contact, and an auxiliary anode electrically connected to said first-mentioned lead-in conductor.

12. In an electric discharge device comprising 15 a sealed envelope, a pair of co-operating electrodes in said envelope at least one of which is a thermionic electrode, a preheating circuit for said thermionic electrode including a thermal switch comprising a bimetallic element and normally closed fixed and movable contacts, said bimetallic element being exposed to the atmosphere in 20 said envelope in direct heat receiving relation to said thermionic electrode and being electrically connected at its fixed end to one end of said thermionic electrode, said movable contact being carried by the movable end of said bimetallic element, means for connecting said fixed contact to the co-operating electrode to shunt the discharge gap between said electrodes and preheat 25 said thermionic electrode when said contacts are closed, and an insulating member having a comparatively small bore closed at one end and exposed to the atmosphere in said envelope through 30 its other end, said fixed contact extending into said bore through said closed end and terminating therewithin, said movable contact extending into said bore through said open end and slidable 35 therein upon flexure of said bimetallic element, said movable contact fitting comparatively snugly in said bore to prevent striking of a discharge 40 from said thermionic electrode to said fixed contact when said contacts are in open position.

RICHARD N. THAYER.
